UNITED STATES PATENT OFFICE

CHARLES A. TRIPP, OF INDIANAPOLIS, INDIANA.

WEB CUTTING, PRINTING, AND FOLDING PRESS.

SPECIFICATION forming part of Letters Patent No. 763,337, dated June 21, 1904.

Application filed August 11, 1902. Serial No. 119,173. (No model.)

To all whom it may concern:

Be it known that I, CHARLES A. TRIPP, a citizen of the United States, residing at Indianapolis, in the county of Marion and State of Indiana, have invented certain new and useful Improvements in Web Cutting, Printing, and Folding Presses, of which the following is a specification.

In the manufacture of cloth bags it is necessary that at various times predetermined lengths of cloth be cut from a web, that these lengths be in many cases printed with a desired pattern, and that said lengths be doubled accurately preliminary to sewing. It has heretofore been customary in many cases to cut the cloth into the desired lengths preliminary to being carried to the printing-press and after they have been printed to pass them through a suitable folding-machine or to fold them by hand. In some cases it has also been customary to pass a continuous web of cloth through a printing-press and thereafter to cut the printed web into desired lengths; but, so far as I am aware, difficulty has been experienced in the last method in producing portions of uniform lengths. It is also necessary in any practical mechanism of this kind to provide means by which the length of the portions may be very accurately determined and regulated within a considerable range of adjustment and by exceedingly small differences, for the reason that a difference of even so little as an eighth of an inch would result in a considerable waste where the output is several thousand cuttings per day. The same is true of any material, such as paper or the like, predetermined portions of which are to be printed or folded.

The object of my invention is therefore to provide a mechanism in a single machine by means of which the forward or free end of a web of cloth, paper, or other material may be grasped, a cutter caused to sever the web at a point between the end thereof and the web-roll at an accurately predetermined and adjustable distance from the free end of the web, and the severed portion of the web carried past suitable printing mechanism and carried through suitable folding mechanism whereby it may be accurately doubled upon itself and

thereafter discharged from the machine, the feeding of the web, the printing, and the folding being accomplished automatically in proper sequence.

The accompanying drawings illustrate my invention.

Figure 1 is a side elevation of my machine, portions being shown in vertical section, the parts being in that position where one section of material has just been severed from the web and the preceding section of material is being folded. Fig. 2 is a similar view with the parts in position where one section of the material is just being severed from the web. Fig. 3 is a detail, on a larger scale, of the feed rolls and tapes and the cutting mechanism. Fig. 4 is an elevation of a modification, omitting the printing mechanism.

In the drawings, 10 indicates the rotary impression-cylinder of a common form of multicolor-printing press, said cylinder being provided with gripper-fingers 11, operated in the usual manner by means of a cam 12, which comes into engagement with a stationary pin (not shown) in the usual manner, a spring (not shown) being used, as usual, to normally hold said fingers in either position. Coöperating with the cylinder 10 may be a rotary type-cylinder 13 and a reciprocating type-bed 14.

Arranged above cylinder 10 and adjustable toward and from said cylinder upon ways 15 is a feed-roll and cutter-carriage 16. Arranged in carriage 16 is a transverse knife 17, and journaled in suitable bearings on the carriage is a rotary cutter-shaft 18, provided with a shear-blade 19, which is slightly spiral, as is clearly shown in Fig. 3, and so arranged as to coöperate with the cutter 17 in a well-known manner. Shaft 18 carries a cam 20, which coöperates with a pin 21, carried by a clamp-arm 22, pivoted at 23 to the carriage and provided with a clamp-finger 24, which at a proper time is brought down upon the cutter 17 immediately back of its cutting edge, so as to hold the web of material during the time of cutting. Leading to the cutter 17 from a point above the same are guides 25, which emanate from a point below the mouth of a pair of feed-rollers 26 and 27, feed-roll 27 being positively driven in the direction indicated 100

by the arrow by means of a chain or other positive drive 28. Coöperating with roller 27 opposite a roller 26 is a roller 29, and the web of material 30, which proceeds from a suitable 5 roll or other source of supply, passes around roller 29, between said roller and the roller 27, and between the roller 27 and the roller 26, falling from thence by its own gravity down the guides 25, past the knife 17, between said 10 knife and clamp 24, and dropping from thence upon the upper sides of endless feed-tapes 31, which are supported upon suitable rollers 32 and 33 above the impression-cylinder 10, guides 34 extending from roller 33 to the impression-cylinder. The rollers 32 and 33 may 15 be positively driven by means of a chain belt 35, which meshes with a sprocket-wheel 35', positively driven by a chain 36 by a suitable counter-shaft 37, which counter-shaft also 20 drives the chain 28. Counter-shaft 37 may be driven from any suitable source of power—such, for instance, as one of the shafts of the press. Cone-pulleys or the speed-changing gearing described in my Patent No. 655,133, 25 issued July 31, 1900, would be interposed in order that the speed of the feed-rolls and feed-tapes may be independently varied with relation to the speed of the impression-cylinder 10. Geared or otherwise connected to the 30 impression-cylinder 10, so as to have the same peripheral speed, is the first folding-cylinder 38, to which in turn is connected the second folding-cylinder 39. Cylinder 38 is in peripheral contact with cylinder 10 and is provided with gripper-fingers 40 of an ordinary 35 form and so arranged that when the gripper-fingers 11 of the cylinder 10 bring the end of the section of material adjacent the cylinder 38 fingers 40 will be in position to engage said 40 section at the time the fingers 11 release the same, the fingers 11 being withdrawn from the cloth by the action of a suitable pin in the usual manner and the grippers 40 gripping the material in the usual well-known 45 manner. Mounted within cylinder 38 and pivoted upon the shaft thereof is a bracket 43, which is adjustable angularly within the cylinder toward and from the gripper-fingers 40. Formed in bracket 43 is a radial slot 44, 50 within which is mounted a folding-plate 45, which may be projected beyond the periphery of cylinder 38 by means of an arm 46, pivoted upon the bracket and swung by means of a lever 47, which is brought into contact with 55 a stationary stop 48. (Shown in dotted lines in Fig. 1.) Cylinder 39 is provided with a peripheral slot, upon one edge of which is arranged a yielding gripper-face 49. Coacting with the gripper-face 49 are gripper-fingers 60 50, which are normally urged toward the face 49 by means of a spring 51. Connected to the gripper-fingers 50 is an operating-arm 52, the end of which engages a stationary cam 53, the arrangement being such that as the cylinder 65 59 rotates cam 53 will operate to with-

draw fingers 50 from the gripping-face 49 and then allow said fingers to coact with said gripping-face immediately after the cloth has been forced into engagement with the gripping-face by means of the folding-plate 45. 70 The cutter 19 is driven in any suitable manner—such, for instance, as chain 54—in such manner that it is given one complete rotation for each rotation of the impression-cylinder 10, the cutter 19 being brought into cutting engagement with the cutter 17, so as to finish its cut at the moment when grippers 11 engage the forward end of the web. 75

In operation the carriage 16 is so adjusted upon its ways that the distance between the gripping position of gripper-fingers 11 and the edge of the cutter 17 along a line which would be naturally assumed by the web between these two points will be equal to the length of material required, and the speed of 80 shaft 37 is so regulated with relation to the speed of the shaft of cylinder 10 that the speed of the feed-rolls 26, 27, and 29 and the feed-tapes 31 will operate to bring the free end of the web into position to be gripped 85 by the gripper-fingers 11 at the instant when said gripper-fingers are in gripping position and at the instant the knives come into action. Bracket 43 is then adjusted within cylinder 38 so that the folding-plate 45 will lie a distance 90 from the gripper-fingers 40 equal to the distance between the forward edge of the severed portions of the web and the desired line of fold. With the parts so adjusted and moving in the directions indicated by the arrows the web after passing through the feed-rolls drops down guides 25, between knife 17 and clamp 24, past the knife, and upon the feed-tapes 31, by which it is moved forward until its forward edge goes into the position 95 shown in Fig. 2, at which time the gripper-fingers 11 of the cylinder 10 will have been brought into position and operated so as to grip the web. Just at this moment cam 20 allows the clamp 24 to drop into engagement 100 with the web and clamp it upon the knife 17. The movement of the cylinder 10 places a slight tension upon the web between the gripper-fingers 11 and the cutter 17 and immediately the cutter 19 is brought into engagement 105 with the web, so as to sever the forward portion thereof. The rotation of the feed-rolls being continuous, the oncoming web banks up behind the clamp 24, and as soon as the cutter 19 passes beyond knife 17 clamp 24 is 110 withdrawn, thus allowing the accumulated portion of the web to fall by its own weight down past the knife 17 and upon the feed-tapes. In the meantime the rotation of the impression-cylinder 10 has caused the severed portion of the cloth to be drawn past the printing-cylinders 13 and the reciprocating printing-platform 14 and around into engagement 115 with cylinder 38, at which time grippers 40 thereof are in position to engage the 120

125

130

forward end of the material, so that it is transferred from the impression-cylinder to the cylinder 38, the material wrapping around cylinder 38 with its point of fold lying over the folding-plate 45. When cylinder 39 has rotated to a point where the folding-plate 45 lies in conjunction with the gripping-surface 49 of cylinder 40, plate 45 is projected by the action of arm 47 and pin 48, so as to carry a bight of the material between the gripping-surface 49 and the fingers 50, whereupon cam 53 allows the fingers 50 to grip the doubled portion or bight upon the gripping-surface 49, whereupon folding-plate 45 is immediately withdrawn, the portion of material being thus folded and transferred to the cylinder 39. When cylinder 39 has rotated so as to bring cylinders 50 at about the point X, Fig. 2, fingers 50 are withdrawn from the gripping-surface 49 and the doubled material falls by its own gravity upon a suitable platform 55.

Claims for the web-cutting mechanism alone have been divided out of this case and incorporated in a divisional application, Serial No. 204,421, filed April 22, 1904.

I claim as my invention—

1. The combination of a web-feeding means, a web gripping and transferring means, a web-stop arranged adjacent the web-gripping position of the gripping means, a pair of shears arranged between the feeding means and the gripping means and so that a web may pass therebetween, and means for intermittently bringing the shears together.

2. The combination of a web-feeding means, a web gripping and transferring means arranged beneath the feeding means, a pair of shears arranged above the gripping means and between said means and the feeding means so that a web may pass therebetween, and means for intermittently bringing the shears together.

3. The combination with a web-feeding means, a transferring means arranged in front of the feeding means to grasp the forward end of the web, a cutter arranged between the feeding means and the transferring means, and means for bringing the cutter intermittently into contact with the web along a line between the transferring means and the feeding means.

4. The combination of a web-feeding means, a clamp, means for intermittently bringing the clamp into engagement with the web in front of the feeding means, a gripping and transferring means arranged in front of the clamp, a cutter, and means for bringing the cutter intermittently into engagement with the web along a line between the transferring means and the clamp.

5. The combination of a web-feeding means, a clamp, means for bringing the clamp intermittently into engagement with the web in front of the feeding means, a gripping and transferring means arranged in front of the

clamp, a pair of shears arranged between the clamp and transferring means, one upon each side of the line of travel of the web from the feeding means to the transferring means, and means for intermittently operating the shears. 70

6. The combination of a web-feeding means, a gripping and transferring means arranged beneath the feeding means, a clamp arranged beneath the feeding means, means for bringing said clamp intermittently into engagement with the web, a pair of shears arranged beneath the clamp and above the gripping means, one upon each side of the line of travel of the web from the feeding means to the gripping means, and means for intermittently operating the shears. 75

7. The combination of a web-feeding means, means for gripping the forward end of the web in front of the feeding means, a severing-cutter arranged between the gripping and feeding means, means for intermittently operating the cutter, folding means, and means for transferring the severed portions of the web to the folding means. 80

8. The combination of a web-feeding means, 90 means for gripping the forward end of the web in front of the feeding means, a clamp arranged between the gripping and feeding means, means for intermittently operating the clamp upon the web, a cutter arranged between the clamp and gripping means, means for intermittently operating the cutter, folding means, and means for transferring the severed portions of the web to the folding means. 95

9. The combination of a web-feeding means, a cylinder provided with gripping means to grip the end of the web, a clamp arranged in advance of the feeding means, a cutter arranged between the gripping means and the clamp, means for intermittently operating the cutter, and folding means arranged in advance of the gripping means. 105

10. The combination of a web-feeding means, a transferring means arranged in advance of the feeding means, means carried by the transferring means for gripping the end of a web, a cutter arranged between the feeding means and gripping means, means for intermittently operating the cutter, and means for adjusting 110 the distance between the cutting and transferring means. 115

11. The combination of a web-feeding means, a transferring means arranged in advance of the feeding means, means carried by the transferring means for gripping the end of a web, a clamp arranged between the feeding means and transferring means, a cutter arranged between the clamp and transferring means, means for adjusting the distance between the cutter and transferring means, and means for intermittently operating the clamp and cutter. 120

12. The combination of web-feeding means, a transferring means, gripping means carried by the transferring means, a web-stop ar- 130

ranged between the feeding means and the transferring means, a cutter arranged between the feeding means and the stop, means for intermittently operating the cutter, and a carrier for carrying the forward end of the web from the cutter to the stop.

13. The combination of web-feeding means, a transferring means, gripping means carried by the transferring means, a clamp arranged between the feeding means and the transferring means, a cutter arranged between the clamp and transferring means, means for intermittently operating the cutter and clamp, and a carrier for carrying the forward end of the web from the cutter to the transferring means.

14. In a web cutting, printing and folding machine, the combination of an impression-cylinder, having means for gripping a web at its forward end, a coacting printing member, web-feeding rolls, a pair of shears arranged between the impression-cylinder and the feed-rolls and above the cylinder, a pair of coacting folding-cylinders the first of said cylinders coacting with the impression-cylinder, means carried by said first folding-cylinder to engage the web portion and transfer the same from the impression member thereto, and coacting means carried by the folding-cylinders for doubling the web portion upon itself.

15. In a web cutting, printing and folding machine, the combination with an impression member and a coacting printing member, of a web-feeding means arranged behind the impression member, cutting means arranged to act intermittently upon the web between the feeding means and the impression member, means for adjusting the distance between the cutter and impression member, means for receiving the severed portions of web from the impression member, and means for doubling said severed portions of the web.

16. In a web cutting, printing and folding machine, the combination with the impression member and coacting printing member, of a

web-feeding means arranged above the impression member, a clamp arranged between the feeding means and the impression member, a cutter arranged between the clamp and impression member, means for intermittently bringing the clamp and cutter into engagement with the web, means for adjusting the cutter toward and from the impression member, tapes arranged between the cutter and impression member to transfer the end of the web to the impression member, a cylinder coacting with the impression member, means carried by said cylinder for receiving the several portions of web, a second cylinder coacting with the first cylinder, and coacting means carried by the two cylinders for doubling the severed portions of the web.

17. In a web cutting and printing machine, the combination, with an impression member, a coacting printing member, and a web-gripping means carried by one of said members, of a web-feeding means for feeding a web toward the gripping means, a severing-cutter acting intermittently on the web between the feeding means and the gripping means, and means for adjusting the distance between the cutter and the gripping means.

18. In a web cutting and printing machine, the combination, with an impression member, a coacting printing member, and a web-gripping means carried by one of said members, of a web-stop arranged adjacent the web-gripping position of the gripping means, a web-feeding means for feeding the web toward the gripping means, a cutter acting intermittently on the web between the feeding means and the stop, and means for adjusting the distance between cutter and the stop.

In witness whereof I have hereunto set my hand and seal, at Indianapolis, Indiana, this 7th day of August, A. D. 1902.
